UNITED STATES PATENT OFFICE.

ARTHUR J. BAZELEY, OF CLEVELAND, OHIO, ASSIGNOR TO THE NATIONAL MALLEABLE CASTINGS COMPANY, OF CLEVELAND, OHIO, A CORPORATION OF OHIO.

CAR-COUPING.

1,100,706.

Specification of Letters Patent. Patented June 23, 1914.

Application filed November 21, 1911. Serial No. 661,540.

To all whom it may concern:

Be it known that I, ARTHUR J. BAZELEY, of Cleveland, Cuyahoga county, Ohio, have invented a new and useful Improvement in Car-Couplers, of which the following is a full, clear, and exact description, reference being had to the accompanying drawings, forming part of this specification, in which—

10 Figure 1 is a side view of the locking member; Fig. 2 is a transverse vertical section of a coupler head with the locking member therein and shown in the knuckle-thrown position; and Fig. 3 is a horizontal longitudinal section showing the locking member in the lockset position.

My invention has relation to certain new and useful improvements in car couplers, and more particularly to the locking and 20 opening member or piece of the coupler.

The present application is a continuation of my pending application Serial No. 468,418, filed December 21st, 1908.

The object of the invention is to provide 25 a car coupler of the automatic type with a combined lock and knuckle-throwing member or piece of novel character having means for holding it in its lockset position on the bottom wall of the chamber of the 30 coupler head.

In the accompanying drawings, the numeral 2 designates a coupler head having an opening 3 in its bottom wall. The locking and opening member consists of a locking head 4, a rear opening member 4^a, and an intermediate connecting member 4^b having in its upper surface a groove or depression 4^c which is arranged to fulcrum, when the piece is lifted, against a projection 2^a on 40 the upper wall of the coupler head. The locking and opening member or piece is also provided with the eye 5 for engagement with a suitable lifting device 8.

When in locking position in the coupler 45 head, this locking and opening piece extends over the tail of the knuckle, the head 4^c fitting in front of the knuckle tail and thus locking the same in position. When it is desired to release the knuckle and to lock- 50 set the lock, the piece is raised until the rear end of the member 4^a is withdrawn from the hole 3 in the floor of the coupler and the

groove 4^c comes into engagement with the fulcruming projection 2^a. The lower end of the member 4^a is thereby moved or swung 55 in a direction which is forward relatively to the drawbar, being thereby brought over and caused to rest upon the ledge or seat 6, which is just forward of the hole 3, and whereby said piece is held in its unlocked 60 and lockset position. In order to permit the member 4^a to rest fully upon this lockset shelf or ledge close up against the adjacent wall of the coupler head, so that it cannot easily be dislodged therefrom by an accidental jar or shock, it is desirable to cut away the side of said member, as shown at 65 4^d, thereby forming a recess which is adapted, in the lockset position of said member, to coöperate with the correspondingly 70 shaped projection 7 on the adjacent wall of the coupler head. This projection 7 forms a part of the coupler wall where, for purposes of strength, all the metal possible is needed. Therefore, any cutting of the wall at this 75 point would result in a considerable loss of strength and is to be avoided, if possible. The lockset ledge or seat 6 is closely adjacent to this projection and owing to the proximity of the projection is relatively in- 80 accessible. There is some difficulty, therefore, in providing for the proper seating of the member 4^a upon this shelf. By providing said member with the reentrant recess 4^d, the locking member is permitted to hug 85 the coupler wall very closely while in lock- set position because the projection 7 enters this reentrant recess and permits the leg 4^a to lie closely against the projection. The 90 construction, therefore, provides for an ade- quate seating of the leg 4^a upon the shelf 6, this full seating being desirable not only to 95 guard against failure to seat initially, but also against the danger of subsequent acci- dental dislodgment. A further pull on the actuating mechanism causes the locking and opening piece to tip or swing on the ful- 100 crum projection 2^a, thereby causing the locking and opening member 4^a to come in contact with the tail 9 of the knuckle and throw the knuckle to its open position. This position of the locking and opening member is shown in Fig. 2.

In moving from the lockset to the knuckle-

throwing position, the lower end of the member 4^a passes through the several positions indicated in dotted lines in Fig. 3.

I claim:—

- 5 A locking and opening piece for car couplers, comprising a locking head, a depending knuckle-opening member substantially parallel with the head and extending below the same, a transverse portion connecting 10 said head and member, said member being adapted to lockset on its lower end and having a reentrant recess at its lower portion,

the walls of said reentrant recess co-operating with a correspondingly shaped portion on the coupler head when the locking member is in lockset position, substantially as described.

In testimony whereof, I have hereunto set my hand.

ARTHUR J. BAZELEY.
